Primary Examiner — Selina Sikder(74) *Attorney, Agent, or Firm* — Johnson & Johnson Surgical Vision, Inc.(57) **CLAIM**

We claim the ornamental design for a foot pedal, substantially as shown and described.

DESCRIPTION

FIG. 1 is a front perspective view of a foot pedal of the present invention;

FIG. 2 is a front perspective view thereof;

FIG. 3 is a top view thereof

FIG. 4 is a left side elevation view of FIG. 1;

FIG. 5 is a right side elevation view of FIG. 2;

FIG. 6 is a front elevation view of FIGS. 1 and 2; and, FIG. 7 is a back elevation view of FIGS. 1 and 2.

FIG. 7 shows features of a foot pedal with broken lines. These features are for illustrating reference of environmental structure only and do not form any part of the claimed design.
